US00D947679S

(12) **United States Design Patent** (10) Patent No.: **US D947,679 S**
(45) Date of Patent: ** Apr. 5, 2022

(54) **BAG**

(71) Applicant: **Avery Dennison Retail Information Services, LLC**, Mentor, OH (US)

(72) Inventors: **Caroline Hughes**, Edwalton (GB); **Daniel Kennedy**, Northampton (GB)

(73) Assignee: **Avery Dennison Retail Information Services LLC**, Mentor, OH (US)

(**) Term: **15 Years**

(21) Appl. No.: **29/797,667**

(22) Filed: **Jul. 1, 2021**

Related U.S. Application Data

(62) Division of application No. 29/697,235, filed on Jul. 5, 2019, now Pat. No. Des. 926,588.
